UNITED STATES PATENT OFFICE.

FRANK KUHN AND FRANK E. SHAILOR, OF DETROIT, MICHIGAN; SAID SHAILOR
ASSIGNOR TO SAID KUHN.

ELECTRICAL HEATER.

1,154,412.

Specification of Letters Patent. Patented Sept. 21, 1915.

Application filed July 1, 1914. Serial No. 848,369.

To all whom it may concern:

Be it known that we, FRANK KUHN and FRANK E. SHAILOR, citizens of the United States of America, residing at Detroit, in the county of Wayne and State of Michigan, have invented certain new and useful Improvements in Electrical Heaters, of which the following is a specification, reference being had therein to the accompanying drawings.

The invention relates to electrical heaters, being more particularly designed for use as radiators for the heating of air in rooms, and adapted for various locations and heating effects.

In the drawings:—Figure 1 is a perspective view of the unit; Fig. 2 is an end elevation showing the unit as mounted on a side wall, and in dotted lines showing various positions of adjustment; Fig. 3 is a longitudinal section showing the adjustable connection between the casing and its supporting bracket; Fig. 4 is a cross section through the heater; and Fig. 5 is a sectional elevation showing the manner of assembling a plurality of sections for units of various sizes.

A are end plates provided with flanged edges B; C is a perforated sheet forming the housing, extending between the end plates A and engaging the flanges B thereof; D is a bottom plate which forms a complementary portion of the housing C and is screwed or otherwise secured to the end plates A to hold the same in properly spaced relation; E is an imperforate shield extending on one side of the housing C and around the top thereof, being properly spaced therefrom and secured by brackets F; and G are supporting brackets secured to the ends A by bolts or other clamping devices H and being capable of adjustment to extend at different angles, as indicated in Fig. 2.

The electrical heating element is arranged within the casing and is mounted preferably upon the base D thereof. This heating element may be formed of any suitable construction, but as shown comprises a series of armored flat units I which are secured to end frames J which also constitute the terminal connections therefor. Various heating effects may be obtained with units of standard resistance by assembling them upon this frame in varying

numbers. The end frames J are secured 55 upon insulator supports K upon the bottom member D and are suitably connected to the terminal block L at the center of the bottom of the casing.

With the construction as thus far described, the casing may be mounted in any desired position and secured by attaching the bracket G to the wall or other support. As shown in Fig. 2, various angles of adjustment may be obtained by loosening the 60 clamping screw H and turning the casing upon the brackets G, and in each position of adjustment the shield E may be arranged to provide proper protection. When the current is turned on the heat generated in 70 the several sections of the unit will be dissipated by radiation and convection, the air adjacent to said sections being free to circulate and to pass through the perforations in the casing.

The distribution of the heat may be altered as desired by mounting the casing in different locations, or by extending the casing to different lengths. Thus, as shown in Fig. 5, the length of a casing may be 80 doubled by placing an intermediate connecting head M between two sections similar to that shown in Fig. 1, or if desired a still greater number of sections may be employed. Again, if a greater heating effect 85 is desired within the same space limits, a larger number of the heating units may be placed within the casing upon the end frame J, the mechanical construction remaining the same. Thus the construction is 90 one which is well suited to manufacture and all the parts may be standardized and variation obtained merely in assembly.

What we claim as our invention is:

An electrical heater, comprising sections 95 each having an end head, a supporting bracket therefor, a perforated casing extending from said head, an electrical heating element within said casing, and intermediate heads for connecting said sections 100 to produce heaters of varying lengths.

In testimony whereof we affix our signatures in presence of two witnesses.

FRANK KUHN.

FRANK E. SHAILOR.
